UNITED STATES PATENT OFFICE

152,664

DESIGN FOR AN ASH TRAY

Norman K. Tschirley, Los Angeles, Calif.

Application May 12, 1948, Serial No. 146,311

Term of patent 3½ years

(Cl. D85—2)

To all whom it may concern:

Be it known that I, Norman K. Tschirley, a citizen of the United States and a resident of Los Angeles, California, have invented a new, original, and ornamental Design for an Ash Tray, of which the following is a specification, reference being had to the accompanying drawing, forming part thereof.

Referring to the drawing:

Figure 1 is a perspective view of an ash tray showing my new design;

Figure 2 is a top plan view thereof;

Figure 3 is a side elevation of the ash tray as viewed in the direction of the arrow 3 of Figure 2; and

Figure 4 is an elevation as viewed in the direction of the arrow 4 of Figure 2.

I claim:

The ornamental design for an ash tray, as shown.

NORMAN K. TSCHIRLEY.
